[57] CLAIM

The ornamental design for a transmission and reception
unit for a mini-earth station, as shown and described.

DESCRIPTION

FIG. 1 is a right side elevational view of a transmission and reception
unit for a mini earth station showing our
new design;

FIG. 2 is a top plan view thereof;

FIG. 3 is a bottom plan view thereof;

FIG. 4 is a left side elevational view thereof;

FIG. 5 is a front elevational view thereof;

FIG. 6 is a rear elevational view thereof; and

FIG. 7 is a top, rear and right side perspective view
thereof;

FIG. 2

FIG. 1

FIG. 4

FIG. 3

FIG. 7

FIG. 5

FIG. 6
